UNITED STATES PATENT OFFICE.

ARTHUR E. REUSS, OF CINCINNATI, OHIO.

RADIOCABINET.

Application filed July 1, 1924. Serial No. 723,584.

It is the object of my invention to provide a radio cabinet of knock-down form, and provide it with means for ready access to the interior of the cabinet for attention to electrical connections or devices therein, and whereby the cabinet may be readily opened for such attention.

In the making of radio sets it is usual to affix the electrical connections to a front panel and a base, or to the front panel only, and to have electric conductors connecting with the electric devices in the inside of the cabinet leading into the cabinet from the outside.

15 It is the object of my invention to provide ready means whereby the top, back and sides of the cabinet may be readily removed, and to further provide an insulating strip which normally forms part of one of the upright 20 walls of the cabinet, which has releasable connection with said wall, and has binding posts thereon, so that said wall may be removed while leaving said insulating strip in place, in order that the electrical connections from 25 the outside to the inside of the cabinet may not be disturbed.

It is the object of my invention, further, to provide ready connecting means between the base and panel and the sides and top, 30 whereby the panel is securely held in place and the top and sides held to the base and panel.

The invention will be further readily understood from the following description and 35 claims, and from the drawings, in which latter:

Fig. 1 is a perspective view of a radio cabinet embodying my invention.

Fig. 2 is a rear elevation of the same partly broken away.

Fig. 3 is a vertical cross-section of the same taken on the irregular line 3—3 of Fig. 2.

Fig. 4 is a detail of the latching means, 45 in horizontal section taken on the line 4—4 of Fig. 1.

Fig. 5 is a vertical cross-section of the latching means, taken on the line 5—5 of Fig. 1, and partly broken away.

50 Fig. 6 is a detail of the insulating strip taken in section on the line 6—6 of Fig. 2.

Fig. 7 is a detail of the releasable cover, taken in section on the line 7—7 of Fig. 1; and,

55 Fig. 8 is a plan view of the back with the sides folded in knock-down relation.

In the present exemplification, the radio cabinet comprises a front panel 11, on which suitable electrical devices of a radio receiving set are suitably mounted, exemplified 60 for instance as comprising an amplifier 14, a vario-coupler 15, a variable condenser 16, a variometer 17, and a silencer 18, each of which is provided with a dial 19 and a knob 20 for adjusting the same and obtaining the 65 proper reception of radio communication in any usual manner.

The electrical devices of these various instruments are at the inside of the front panel. The front panel is a panel of electric insulating material, for instance, so-called bakelite. Electrical conductors, shown as wires 24, connect with these various instruments, and lead to the outside of the cabinet, and electrical conductors 25 may 75 also be connected with these instruments and with suitable electrical instruments 27, 28, mounted on the base 31, usually of wood, these electrical instruments being represented as tube amplifiers and batteries respectively.

Electrical conductors 34 may have electrical connection with said latter instruments and be extended outside of the cabinet.

The cabinet is provided with a back 41, 85 sides 42, 43, and a top 44, which are preferably arranged knock-down with relation to the base and panel.

The base is provided with a channel-piece 46, secured thereto by screws 47. The front 90 panel is releasably received in said channel-piece.

The sides are provided with front flanges 49 received in front of the front panel. The sides are also provided at their rear ends 95 with inturned flanges 51, said flanges connecting with the respective ends of the back by means of hinges 52, 53, whereby the sides can be arranged substantially parallel with the back when the parts are in knock-down 100 relation, for taking up little space.

The top is provided with a rear flange 55, a front flange 56, and end flanges 57, the front flange and the end flanges having reversely bent ends 58. The front flange is received in front of the top edge of the panel, and the end flanges are received at the outside faces of the side walls, for positioning the front panel and the side walls with relation to the top, and preventing outward movement of the front panel and side walls. 110 The reverse bending of the front flange

and the end flanges provides an extended edge for the top, extended beyond the front and side walls.

The front panel is received in the channel 5 of the channel-piece of the base and has the front flanges 49 of the side walls and the front flange 56 of the top received in front of the same.

The base is provided with a keeper 61 10 fixed thereto adjacent each end thereof inside the positions of the side walls. A latch-lever 62 is provided with a latch 63 and is pivoted to the side wall on a pivot-pin 64, secured to said side wall and located adjacent 15 cent to the latch.

The lever extends upwardly parallel with the side wall, and is provided with a front flange 65 and with a top flange 66. The pivot-pin 64 is closely adjacent to the channel-piece 46 and, in order to provide ready swinging of the latch-lever on its pivot, the heel of the latch is provided with a rounded face 67. There are side walls 71 provided at the keeper to relatively locate the latch and the keeper in sidewise relation whereby lateral position of the side wall is determined, and a top wall 72, whereby the sides are held downwardly upon the base.

The upper end of the latch lever is secured to the top, as by means of a screw 73 30 passing through a hole in the top and threaded in a threaded hole in the upper flange 66 of the latch-lever.

The relation of the parts is such that when 35 the latch-lever is swung to fix the same in place, it presses upon the front panel for pressing the front panel against the flanges in front of the same for readily securing the front panel in place. The latch-lever and 40 its keeper secure the sides to the base, and the fastening means at the top of the latch-lever secure the top to the sides and base. There is one of the latch-levers and keepers at each end of the front panel.

45 Clips 76 are provided, by means of which the rear wall is secured to the base, screws 77 being received therethrough and screwing into the base, and screws 78 being received therethrough and being screwed into threaded holes in the lower edge of the rear wall.

The top is provided with an opening 81 arranged to be closed by a cover 82. The margin of the opening has a flange 83 thereabout, and the cover has a marginal flange 55 84 coacting therewith. The cover has spring 85 clips fixed thereto, which are received under the margin of the opening in the top, for releasably holding the cover to the top. The cover is readily removed by prying under 60 the flange with a raising motion.

One of the upright walls of the cabinet, represented as the rear wall, is provided with a recess 87, forming an opening at its bottom margin. A binding-post panel 88 65 of electric insulating material normally

closes said opening. This binding-post panel has binding posts 89 passing therethrough, having conductor clamps 90 at their inner ends, by means of which the respective wires at the inside of the cabinet are releasably secured to said binding posts, and conductor clamps 91 at the outside of the cabinet by means of which electric wires 92 are releasably secured to said binding posts, the latter connecting with suitable electric devices of 70 the radio receiving apparatus at the outside of the cabinet.

The binding-post panel is positioned by means of clips 93, shown secured to the base 31 by screws 94, the binding-post panel being secured to these clips by passing the shanks of selective ones of the binding-posts through said panel and electric insulating thimbles 95 in the clips, the binding posts being clamped in said panel and thimble by 85 the clamps at the ends of the binding posts.

The releasable connection between the rear wall and the binding-post panel is shown as formed by contact between the margin of the opening with the margin of the binding-post panel, the rear wall being held in place by the clips 76.

The back, side walls and top and cover of my improved cabinet are arranged to be struck up from sheet metal, making a cheap 95 and strong construction, readily arranged for knock-down purposes and, if desired, the inner faces thereof may have an insulating lining applied thereto, the insulating lining of the side walls being shown at 96, 100 that of the rear wall being shown at 97, that of the top being shown at 98, and that of the cover being shown at 99.

Having thus fully described my invention, what I claim as new, and desire to secure 105 by Letters Patent, is:

1. In combination, a radio cabinet comprising a base, a panel, a top, and sides, and means securing said panel between said base and said top including keepers on said base, latch-levers pivoted to said sides comprising latches received by said keepers, and securing means between said latch-levers and said top, and arranged whereby said latch-levers exert pressure on said panel. 115

2. In combination, a radio cabinet comprising a base, a panel, a top and sides, said base, said sides and said top provided with flanges in front of said panel, keepers on said base, latch-levers pivoted to said sides 120 adjacent to said panel, said latch-levers including latches complementary to said keepers, and securing means for said latch-levers so arranged as to cause said latch-levers to press said panel toward said flanges. 125

3. In combination, a knock-down radio cabinet comprising a base, a panel, hingedly connected back and sides and a top, said sides adapted to be substantially parallel with said back when in knock-down relation, 130

means for securing said back to the rear of said base, keepers on the front portion of said base, latch levers including latches received under said keepers, and securing means between said top and said latch-levers adjacent to said panel.

4. In combination, a knock-down radio cabinet comprising a front panel and a base, a top and sides provided with flanges in front of said panel, keepers on said base adjacent said sides, latch-levers including latches complementary to said keepers, pivots on said sides for said latch-levers adjacent to said base, said keepers and latches provided with complementary top and side walls to relatively connect the same in up and down and lateral relations, and connecting means between the upper ends of said latch-levers and said top arranged whereby said latch-

levers press said panel toward said flanges, 20 and whereby said base, sides, top and panel are fixed together.

5. In combination, a radio cabinet comprising a front panel, a base, and knock-down back, sides and top, said back and 25 sides forming walls, the lower end of one of said walls being provided with a recess, a panel normally closing said recess, said last-named wall releasable from said last-named panel, and releasable connecting means connecting said back, said sides and said top with said front panel and said base, and arranged whereby said back, top and sides are removable from said front panel, said base and said last-named panel. 30

In testimony whereof, I have hereunto signed my name.

ARTHUR E. REUSS.
